US00D554025S

(12) **United States Design Patent** (10) Patent No.: **US D554,025 S**
(45) Date of Patent: **** Oct. 30, 2007**

(54) **MOTORCYCLE STAND**

5,826,838 A * 10/1998 Forbes 248/97

(75) Inventor: **Charles Van Valkenburgh**, Huntsville, AL (US)

* cited by examiner

(73) Assignee: **Pit Bull Products, Inc.**, Huntsville, AL (US)

Primary Examiner—Cathron Brooks

Assistant Examiner—Linda Brooks

(74) Attorney, Agent, or Firm—Adam K. Sacharoff; Much Shelist

(**) Term: **14 Years**

(57) **CLAIM**

(21) Appl. No.: **29/249,403**

The ornamental design for the motorcycle stand, as shown and described.

(22) Filed: **Oct. 5, 2006**

DESCRIPTION

(51) LOC (8) Cl. 12-11

FIG. 1 is a perspective view showing the new design;

(52) U.S. Cl. **D12/115**

FIG. 2 is a front side view of FIG. 1;

(58) Field of Classification Search D12/115,

FIG. 3 is a back side view of FIG. 1;

D12/120; 211/5, 17-22, 182; 248/97, 127,

FIG. 4 is a left side view of FIG. 1;

248/153, 158, 175, 176.1, 188.1, 188.8; D6/462,

FIG. 5 is a top planar view of FIG. 1; and,

D6/499; 280/293, 298

FIG. 6 is a bottom planar view of FIG. 1.

See application file for complete search history.

The circular broken lines represent boundaries of the claimed design and form no part thereof.
